UNITED STATES PATENT OFFICE.

JOHN D. METS, OF DUBUQUE, IOWA.

BOOK.

No. 904,076.

Specification of Letters Patent.

Patented Nov. 17, 1908.

Application filed September 3, 1907. Serial No. 391,047.

To all whom it may concern:

Be it known that I, JOHN D. METS, citizen of the United States, residing at Dubuque, in the county of Dubuque and State of Iowa, 5 have invented certain new and useful Improvements in Books, of which the following is a specification.

My invention relates to hotel registers with special reference to such as have edges 10 extending beyond the edges of the book and furnishing space for advertising matter.

The leading object of my invention is to construct these extension edges separate from the registers and supply them with 15 means whereby they can be conveniently attached to, and detached from the covers of the book.

The following specifications will fully illustrate and describe my invention when 20 taken in connection with the drawings accompanying the same and forming a part hereof.

Figure 1. is a plan view of a hotel register with one of the extension edges removed and 25 only a few leaves in the book. Fig. 2. is a plan view of one of the separate edges removed. Fig. 3. is a perspective view of a portion of the attaching frame that surrounds one edge and ends of the extension 30 edges and by which the edges are attached to the cover of the book. Fig. 4. is a cross section on line $x-x$ of Fig. 1. Fig. 5. is a plan view of a sustaining plate. Fig. 6. is a perspective view of the outside of the extension 35 edge. Fig. 7 is a perspective view of one end of the book showing the manner in which the part 25 clasps over the end and against the longitudinal edge of the cover against the hinge and between the hinge and 40 the back of the book.

Like characters of reference denote corresponding parts in each of the figures.

Reference being had to the drawings 2 denotes a hotel register which consists of a 45 blank book ruled in a suitable manner and where used as a hotel register, provided with space for the name of the hotel and beneath, the usual spaces for registration for guests. The leaves 5 of this book extend to the edges 50 of the covers 6. The lids of the covers are split or recessed out and in this recess is inserted a steel plate 10 for the purpose presently to appear. The removable edges 12 are formed of a board 14 with a glass covering 15 and between the board and glass is inserted a card on which is printed or

stamped various advertisements 16. The edges thus formed are surrounded on the ends and longitudinal outer edge by a frame 18 constructed preferably of channel bar 60 shape with the sides 20 extending over the edges of the board and glass 15. Preferably in the longitudinal center of each of the outer edges of the lids of the cover is a recess 7 in which is inserted the steel plate 10 65 that projects beyond the edge of the cover and engages a similar recess 9 in the removable edge of the cover for the purpose of rigidly holding the removable edges and cover of the book in the same plane. Instead 70 of a plate 10 the edges may be dovetailed to the edges of the cover.

The frame 18 extends beyond the removable edge and forms clasping arms which 75 clasp the ends of the lids of the cover but where they extend along the entire end of the lids they are each preferably provided with a hook 25 that is bent over or around upon the inner longitudinal edge of the lids and prevent the removable edge from being 80 withdrawn. These arms may extend only part of the distance along the ends of the cover and be removably secured to the cover in any convenient manner.

For the purpose of preventing the frame 85 18 from marring or otherwise injuring the counter or rest upon which the book is sustained, there is secured along upon the outer surface of the board 14 near to the inner edge of the frame a rib 30 of some soft, 90 pliable material such as a cotton cord. The cord may not extend the whole length of the extension edge but may be broken and form knots or pins to rest on the counter.

In applying the removable edges the plate 95 10 is inserted in the recess of the cover and the arms being made of spring material may be readily sprung out sufficiently to allow the cover to be slid in till it contacts with the inner edge of the removable edge 12 and the plate 10 will enter the recess or split in the edge of the cover of the book then the arms of the frame are released and will 100 clasp the ends of the cover and the hook 25 engage over the inner edge of the cover and hold the edge 12 in position.

When the register is filled the register is 105 released by springing out the arms of the frame and another register of the same size is readily put in its place.

It is manifest that various constructions may be made of the means whereby the arms

are removably attached to the cover and the cover and edges held in the same plane without departing from the spirit of my invention and I do not desire to be limited to this 5 specific mode of construction or application.

Having now described my invention, what I claim is:—

1. In a device of the character described, a book cover, a removable edge made separate, and a frame adapted to engage the removable edge and ends of the cover and removably secure the edge to the cover. 10
2. In a device of the character described, a book cover, a separate removable edge, a frame adapted to engage the edge and removably secure the edge to the cover of the book, and means secured to the outer side of the removable edge for preventing the frame or edge from contacting with the support on 15 which the book rests.
3. In a device of the character described, a book cover, a separate removable edge, a frame engaging the removable edge and cover and detachably uniting them together, and a yielding rib or raised surface secured 20 to one side of the removable edge near the frame for preventing the frame from marring the book support.
4. In combination with hotel registers or other books a removable or detachable edge, and means engaging the ends of the lids of the cover for removably attaching the edge to the longitudinal edge of the cover. 30
5. In a device of the character described, a book cover, separate removable edges 35

adapted to contact with the edges of the cover, means for holding the edges of the cover and the removable edges in the same plane, and means for removably attaching the removable edges to the edges of the 40 cover.

6. In a device of the character described, a book cover, a separate and removable edge consisting of a base board, a transparent covering for said board, in combination with 45 a frame engaging the removable edge and the ends of the cover and removably uniting them together.

7. In a device of the character described, a book cover, a separate and removable edge 50 consisting of a base board a transparent covering for said board with space between for advertisements, a channel-bar frame in which the board and covering are held said frame engaging the ends of the cover and 55 detachably uniting the removable edge to the cover, and means connected to the cover and edge for holding them in the same plane.

8. In a device of the character described a book cover, a removable edge separate 60 from the cover, a frame adapted to partly surround the edge, and means attached to the frame for removably attaching the frame with the separate edge to the cover.

In testimony whereof I affix my signature, 65 in presence of two witnesses.

JOHN D. METS.
